METAL BENDING AND STRETCHING APPARATUS

James S. Nielsen, Stow, Ohio, assignor to Good-year Aircraft Corporation, Akron, Ohio, a corporation of Delaware

Application June 7, 1943, Serial No. 489,911

3 Claims. (Cl. 153—48)

1

This invention relates to metal working apparatus, and, more particularly, is concerned with apparatus of this type for bending metal and simultaneously giving the metal a controlled stretch.

It is the general object of the invention to provide improved apparatus for bending metal sheets or lengths and for simultaneously giving an accurately controlled stretch to the metal being worked.

Another object of the invention is to provide relatively inexpensive, easily handled and operated, long wearing apparatus of the character described which is adapted to production operations, and which can be employed to give a controlled stretching to metal during a bending operation thereon.

Another object of the invention is the provision of apparatus including exactly controlled and positioned work clamping jaws for supporting the metal to be worked, and including means for effecting relative movement between the work and a die to achieve a controlled bending and stretching of the work around the die.

Another object of the invention is to provide metal bending and stretching apparatus including pivotally mounted work engaging jaws which are free to follow and align themselves.

The foregoing and other objects of the invention are achieved by the provision of apparatus including a die, means supporting the die, means for gripping opposed portions of a length of metal, means for effecting relative movement between the die supporting means and the metal gripping means to bend the length of metal about the die, and means for positively controlling the position of the metal gripping means to apply a controlled stretching to the length of metal during the bending operation.

For a better understanding of the invention, reference should be had to the accompanying drawings wherein Figure 1 diagrammatically illustrates in side elevation one embodiment of apparatus incorporating the principles of the invention; and Figures 2 to 6 are all similar to Figure 1 but show other embodiments of the invention.

In the drawings, and having particular reference to Figure 1, the numeral 10 indicates generally a suitable base which centrally supports a

2

hydraulic cylinder or cylinders 12, or other suitable means, for example a screw or toggle mechanism adapted to move a die supporting table 14 toward or from the base 10. The die table 14 removably carries a die 16 which is adapted to be engaged laterally against a length or sheet of metal M comprising the material to be formed over the die.

The metal M is gripped at its ends in suitable 10 jaw means 18 each mounted on a turnbuckle 20 in turn pivotally secured, as at 22, to portions of the frame 10.

In the operation of this embodiment of the invention the metal M is mounted between the jaws 18 and the turnbuckles 20 are tightened to give a controlled stretch to the metal. Thereafter, or simultaneously with the stretching of the metal M, the hydraulic cylinder or cylinders 12 are energized to move the die 16 laterally against the metal M to thereby achieve a combined bending of the metal around the die and a further stretching of the metal. Sometimes the die is relatively flat, or again, a die is shaped to form metal lengths with relatively wide flange portions. In operations of this type it is generally advisable to impart certain added stretch to the metal M by tightening the turnbuckles 20 during the movement of the die 16 against the metal, with the added stretch insuring that the flanges on the metal are free of wrinkles or buckles. On the other hand, when the metal M is formed over a die having a high crown to impart a considerable bend to the metal, specifically without the formation of flanges, it is often advisable to slack off on the turnbuckles 20 during the metal bending and stretching operation because the considerable movement of the die into the work piece to bend the work piece around a large curve of short radius imparts a considerable stretch to the metal. This stretch is controlled by slackening off on the turnbuckles 20 to give an exactly controlled stretch to the metal M during the bending operation to thereby provide a finished work piece having a minimum of spring-back and no wrinkles or buckles and not over stressed or ruptured. The pivotal connections 22 between the base 10 and the turnbuckles 20 insures that the jaw members 18 and the turnbuckles 20 are free to turn and follow the metal

40 M at all times as it is bent around the die.

The embodiment of the invention illustrated in Figure 2 is identical to that illustrated in Figure 1, with the single exception that the turnbuckles 20 have been replaced by hydraulic cylinders 30 which provide a simplified and more readily actuated control for the jaw members 18. It will be understood that suitable control means are provided in conjunction with each one of the hydraulic cylinders 30 so that the pistons and piston rods of these cylinders which mount the jaws 18 can be moved positively by hydraulic action in either direction to impart further stretch to the metal M or to slack off on the application of stretch to the metal. Except for the numerals 30 used to designate the hydraulic cylinders, like numerals have been employed in Figure 2 to designate identical parts shown in Figure 1 except that in Figure 2 the suffix *a* has been added to the numerals.

In the form of the invention illustrated in Figure 3, parts identical to those illustrated in Figure 1 have been indicated by like numerals except that the suffix *b* has been added. In this form of the invention the die 16b is made stationary and the hydraulic cylinders 30b are pivotally connected, as at 22b, with blocks 36 which are slidably supported for vertical movement in the base 10b so as to effect relative movement between the metal M and the die 16b under the action of hydraulic cylinders 38 or other suitable means for controlling the position of the blocks 36.

The embodiment of the invention illustrated in Fig. 4 is like the form of the invention shown in Figure 2 except that the fluid pressure cylinders 30c are pivotally secured, as at 22c, to brackets 42. These brackets are made slideable in beds 44 fastened to the base 10c and each bracket's position on its bed is adjustably fixed by a threaded spindle 46 operated by a hand wheel nut 47. A two armed lever 48 swingable about a pivot 50 is engaged by the fluid pressure cylinder 30c and connects to the jaw 18c. The machine shows in dotted lines the position of the working mechanism of the machine and the working material after the bending and stretching operation. It will be recognized that parts of Figure 4 identical to portions of Figure 2 have been indicated by like numerals but with the suffix *c* being added.

A further embodiment of the invention is shown in Figure 5, which illustrates in full lines the apparatus in the position with the material shaped around the die and in dotted lines the position of the apparatus before the stretching and bending of the material. The apparatus of Figure 5 is generally similar to that of Figure 3. However, Figure 5 includes a movable die 16d and has the side cylinders 38d mounted on supports 60 which are movable on the beds 62. Movement of the supports 60 is achieved by means of fluid pressure cylinders 64, pivotally secured at one end to the cylinder 12d and having their piston rods connected to the supports 60. This arrangement has the advantage of permitting the bending of bars or sheets to more than half a circle, and the fact that the cylinders 38d and 12d operate in opposite directions reduces the overall height of the machine. Like numerals have been employed in this figure of the drawings to indicate like parts to other figures except that the suffix *d* has been added.

Still another form of the invention is shown in Fig. 6. The fluid pressure cylinders 30e in this case are adjustably mounted on arms 70

swingable about pivots 72 on a frame 74 having a work table 76 from which at right angle to the arms extends a supporting beam 78 having mounted thereon a threaded spindle 80 which engages a nut 82. The nut 82 is moved to the desired position along the spindle 80 by rotating the spindle by means of the pulley 88 operated by an electric motor (not shown).

Links 84 pivotally attached with their one end 10 to the nut 82 and with their other end to the arms 78 swing the arms toward the beam 78, as shown in the dotted lines when the nut 82 is moved on the spindle. This action bends a work piece M held between the jaws 18e around 15 a form 86 fastened to the table 76. While the work piece is bent around the form sufficient stretch is imposed on it by the cylinders 30e to keep the material from wrinkling. Parts similar to like parts in the other figures have been indicated in Figure 6 by the same numeral but 20 the suffix *e* has been added.

It will be recognized that each one of the embodiments of the invention illustrated in Figures 2 to 6 functions in a manner generally similar 25 to that above described in conjunction with Figure 1, namely, the metal to be worked is given a controlled bending and stretching operation by effecting relative movement between the die and the jaw members supporting the metal, and 30 with the position of the jaw members being accurately controlled during the bending operation to impart into the metal an exactly controlled stretching whereby all wrinkles and 35 buckles are removed from the metal and spring back is kept to a minimum all without over stressing or rupturing the metal work piece.

Accordingly, the objects of the invention have been achieved by the provision of relatively inexpensive and readily operated apparatus for 40 bending and simultaneously positively stretching a metal work piece in exact and controlled amounts and to desired contours. The improved apparatus is readily adapted to operate on metal work pieces of a wide variety of forms or cross 45 sectionals shapes and contours, and is particularly adapted to operations upon metal pieces having large flange portions or bends on sharp radii where heretofore portions of the metal have been either over stretched or under stretched.

While in accordance with the patent statutes the invention has been specifically illustrated and described in certain of its best known embodiments, it should be clearly understood that the 55 invention is not to be limited thereto or thereby, but that the scope of the invention is defined in the appended claims.

What is claimed is:

1. Metal forming apparatus including a pair of gripping jaws adapted to grip opposite ends of a length of metal to be formed, a die, hydraulic means for moving the die toward and from a metal length gripped between the jaws, mounting means pivotally supporting each jaw for tilting movement toward and from the die, a hydraulic means associated with each of the mounting means for moving said mounting means in a direction substantially parallel to the direction of movement of the die, and a hydraulic means associated with each mounting means for moving it in a direction at substantially right angles to the movement of the die.

2. Metal forming apparatus including a bed, a die positioned centrally of the bed, hydraulic means for moving the die substantially vertically

with respect to the bed, supports slidably mounted for substantially horizontal movement on the bed on each side of the die, hydraulic means associated with each support for moving it toward or from the die, a block slidably carried for substantially vertical movement on each support, a hydraulic means carried by the support and controlling the vertical position of the block, and a gripping jaw pivotally secured to each block for tilting movement toward and from the die.

3. Metal forming apparatus including a bed, a die positioned centrally of the bed, hydraulic means for moving the die substantially vertically with respect to the bed, supports slidably mounted for substantially horizontal movement on the bed on each side of the die, means associated with each support for moving it toward or from the die, a block slidably carried for substantially vertical movement on each support, means carried by the support and controlling the vertical posi-

tion of the block, and a gripping jaw pivotally secured to each block.
